(57) **CLAIM**

The ornamental design for a brush, as shown and described.

DESCRIPTION

FIG. 1 is a perspective view of a brush showing my invention;

FIG. 2 is a front side view thereof;

FIG. 3 is a back side view thereof;

FIG. 4 is a left side view thereof, the right side being a mirror image thereof;

FIG. 5 is a top side view thereof; and,

FIG. 6 is a bottom side view thereof with the bristles removed for clarity.

The contrast in shading techniques on the brush handle in FIGS. 1-6 designates a contrast in appearance, accompanied for example by color, material, and/or texture.

The broken lines of the hole and the bristles are for illustrative purposes only and form no part of the claimed design. The bottom face of the brush head section in FIG. 6, as indicated by broken lines, is also for illustrative purposes only and forms no part of the claimed design.
